Primary Examiner—Stella M. Reid*Assistant Examiner*—Mark A Goodwin(74) *Attorney, Agent, or Firm*—Morgan & Finnegan, LLP(57) **CLAIM**

The ornamental design for a shovel loader, as shown and described.

DESCRIPTION

FIG. 1 is a front perspective view of a shovel loader showing my new design;

FIG. 2 is a rear perspective view thereof;

FIG. 3 is a front view thereof;

FIG. 4 is a rear view thereof;

FIG. 5 is a top plan view thereof;

FIG. 6 is a left side elevational view thereof; and,

FIG. 7 is a right side elevational view thereof.

The bottom of the article forms no part of the claimed design.
